United States Patent Office

Des. 213,422
Patented Mar. 4, 1969

213,422

BOTTLE

William C. Sizer, P.O. Box 832,
Minneapolis, Minn. 55440

Filed Mar. 8, 1968, Ser. No. 10,903

Term of patent 3½ years.

U.S. Cl. D9—118
Int. Cl. D9—01

FIG. 1

FIG. 3

FIG. 2

FIG. 4

FIG. 1 is a top plan view of a bottle, showing my new design;

FIG. 2 is an elevational view;

FIG. 3 is a vertical sectional view taken through the center of the bottle; and

FIG. 4 is a bottom plan view thereof.

I claim:

The ornamental design for a bottle, substantially as shown.
